DISPLAY CHARACTERS

Thomas G. Faulkner, % Faulkner's Laboratories,
4504 E. Hillborough, Tampa, Fla.
Filed Sept. 9, 1958, Ser. No. 759,996
3 Claims. (Cl. 40—140)

This invention relates to display characters and is particularly concerned with a character of the type disclosed in my prior application Serial No. 754,206, filed August 11, 1958, and entitled Changeable Exhibitors. While the present inventive concept is not limited nor confined to any particular type of material, shape or thickness of the character, the invention is here illustrated in the form of a relatively thin, preferably translucent, plain or colored plastic letter which is adapted to be as secured on the front face of a sign board by character supporting rods.

In the invention of my prior application above referred to, the inventive concept was shown as including the attachment of characters of this type to supporting rods by the use attaching clips formed to define a circular rod receiving opening and flexible or resilient fingers extending from the opening to receive the rod through a reduced throat between inwardly extending projections of the terminal ends of fingers. This same inventive concept comprehends the formation of the rod receiving aperture and the rod engaging throat defined by the integral material of the letter itself as distinct from the use of a clip element, whether such clip be formed integrally with the letter or integrally attached thereto by plastic welding as suggested in my prior application. The present invention therefore constitutes a specific embodiment of the broader concept of my earlier application, and thus this application is a companion application to said prior application Serial Number 754,206, filed August 11, 1958, the subject matter of which and the object features and advantages therein set forth being here included by reference.

The specific structural features of this form of the invention will be more fully understood from the consideration of the following specification taken in conjunction with the accompanying drawings in which:

FIGURE 1 is a perspective view of the combination of a letter and sign board formed in accordance with the present invention.

FIGURE 2 is similar view of a sign board and letter combination showing a corrugated type of sign board, and

FIGURE 3 is an end elevation of a letter formed in accordance with the present invention.

Referring now in detail to the drawings, it will be seen that the numeral 10 indicates a sign board panel here shown as of relatively rigid material 10 presenting a flat front face 11. It will of course be understood that the invention is not limited or confined to any specific style or material of sign board and that it may be of such configuration as desired and may be of translucent plastic material so as to provide for the admission of light from a source of illumination behind the board. For supporting characters on the front face 11 of the board 10, rods 12 are provided, preferably in the spaced parallel position illustrated. The rods 12 are here shown of generally circular form but may be of various modified cross sections such as those presented in my co-pending application above referred to. The rods also may be of any desired material but it is here suggested that the rods be of plastic material so as to provide for the integral attachment thereof to the sign board by plastic welding.

The character here presented is indicated generally by the numeral 13 and is of hollow form including parallel sides 14 extending rearwardly from the flat aspect surface 15. Thus the arms of the letter are virtually U-shaped in cross-section. For securing the letter on the

2

sign board the sides 14 are provided with circular apertures 16 each intersecting the rear edge of the side along a chord line of the short length best shown in FIGURE 3, so that each aperture is open to the rear edge through a restricted throat 17 between inwardly extending projecting fingers 18. It will be understood that the throat is of slightly less width than the diameter of the rods and that the material of the letter is so resilient as to permit the fingers to spring past and over the rod so that the rod may be seated within the aperture and the letter retained by the yieldable engagement of the rod by the fingers. It will of course be noted that parallel areas of each letter are cut in the manner described to provide their reception over the rods and that the letters may be formed with any such number of pairs of receiving apertures as the number of supporting rods of the board dictate.

In that form of the invention shown in FIGURE 1, the board is flat paneled and the letter edges closely approach the surface of the board or may be in actual contact therewith to give the appearance of a single unitary structure. In that form of the invention shown in FIGURE 2 the panel 20 is of corrugated form and the rods 21 are secured to the crests of the corrugation by plastic welding. The letter 22 of this figure is formed in the same manner as described in respect to the letter of FIGURE 1 and in this case the attachment of the letter is such that the letter edges are spaced from the valleys of the corrugations and thus permit air circulation and drainage of water from behind the letter.

From the foregoing it will be seen that the present invention provides for the attachment and ready removal of a letter by means of a securing key hole opening formed in situ in the edges of the letter. As set forth in my prior application the letter thus secured may be readily removed by a straight outer motion or by a tilting action, in either instance the flexing of the material or throat permits ready removal and application, such flexibility providing a firm securement of the letter.

It will be understood that in the practice of the invention numerous changes, modifications and the full use of equivalents may be resorted to without departure from the spirit or scope of the invention as outlined in the appended claims.

What I claim is:

1. In combination, an upright sign board of translucent plastic material having a plurality of co-planar surface areas spaced laterally and vertically apart, upper and lower plastic rods of circular cross section spaced vertically apart in horizontally extending parallelism on said board, each rod making line contact with certain of said laterally spaced co-planar areas and being secured to the board by welded connection of the plastic material of the board and rod, and a plastic translucent sign character comprising a hollow flexible body having a pair of spaced parallel rearwardly extending vertical sides terminating in a pair of horizontally spaced co-planar edges, each of said sides having vertically spaced upper and lower apertures each of generally circular shape of the same radius as that of the rods, each aperture intersecting the rear edge of the character along a chord line of relatively short length, and said character being detachably and interchangeably mounted on said board by snapping engagement of the upper and lower rods into said upper and lower apertures respectively, thereby positioning certain portions of the rear edges of the character in substantial contact with certain of said co-planar areas of the board.
2. The combination claimed in claim 1 in which the board has a flat smooth front surface and each of the rods makes contact with the board substantially continuously throughout the length of the rod.

3. The combination claimed in claim 1 in which the board is provided with vertically extending corrugations having crest lines of equal height and each of the rods is welded to the crest lines of laterally spaced corrugations.
